(57) **CLAIM**

The ornamental design for a sump pump controller, as
shown and described.

DESCRIPTION

FIG. 1 is an isometric view of a front, top, and right side of
an embodiment of an ornamental design for a sump pump
controller;

FIG. 2 is an isometric view of a rear, bottom, and left side
of the sump pump controller of FIG. 1;

FIG. 3 is a top plan view of the sump pump controller of
FIG. 1

FIG. 4 is a bottom plan view of the sump pump controller
of FIG. 1;

FIG. 5 is a left side elevational view of the sump pump
controller of FIG. 1;

FIG. 6 is a right side elevational view of the sump pump
controller of FIG. 1;

FIG. 7 is a front elevational view of the sump pump
controller of FIG. 1;

FIG. 8 is a rear elevational view of the sump pump controller
of FIG. 1;

FIG. 9 is an environmental isometric view of the front, top,
and right side of the sump pump controller of FIG. 1; and,
FIG. 10 is another isometric view of the front, top, and right
side view thereof showing surface indicia in broken lines.
The broken lines immediately adjacent to the shaded sur-
faces form a boundary of the claim and form no part of the
claimed design.
